UNITED STATES PATENT OFFICE

OSCAR H. PIEPER, OF ROCHESTER, NEW YORK

DENTAL APPARATUS

Application filed November 15, 1929. Serial No. 407,526.

The present invention relates to dental apparatus and more particularly to a spraying device together with means for supplying both warm and cold water under pressure for spraying purposes, as required for example by the dental profession under different conditions in the treatment and care of the teeth, one object being to provide improved means of this class which is compact, convenient to operate and efficient in service.

A further object of the invention is to provide an improved valve construction for controlling and regulating the flow of the warm and cold water in its passage to and from the fluid holding container.

A further object of the invention is to provide improved means for locking or holding the container in position upon the supporting means therefor.

A further object is to provide improvements in the construction of the electric heating apparatus for the fluid holding container.

A still further object of the invention is to provide an improved conduit for conveying the fluid from the container to the nozzle of the spray head.

To these and other ends the invention resides in certain improvements and combinations of parts, all as will be hereinafter more fully described, the novel features being pointed out in the claims at the end of the specification.

In the drawings:

Fig. 1 is a view in elevation of a device embodying the invention;

Fig. 2 is an elevation as viewed from the right of Fig. 1;

Fig. 3 is a top plan view of the device shown in Fig. 1;

Fig. 4 is an enlarged transverse section taken on line 4a—4a of Fig. 1 showing the arrangement of valves for controlling the fluid passages leading to and from the liquid holding container;

Fig. 5 is a somewhat similar view with valves adjusted to a different position;

Fig. 6 is a vertical section taken on line 6a—6a of Fig. 4;

Fig. 7 is a vertical section taken on line 7a—7a of Fig. 5;

Fig. 8 is a detailed section taken on line 8a—8a of Fig. 4;

Fig. 9 is a top plan view of the heating unit with the fluid holding container removed;

Fig. 10 is a bottom plan of the container showing the thermostat thereon for regulating the supply of current to the heating coil;

Fig. 11 is a vertical section taken on line 11a—11a of Fig. 9;

Fig. 12 is an enlarged vertical section taken on line 12a—12a of Fig. 3 showing the means for locking the fluid holding container within the heater;

Fig. 13 is an enlarged fragmentary sectional elevation of the coupling by which the nozzle tube is connected with the outlet passage of the fluid holding container;

Fig. 14 is a fragmentary part sectional elevation of the spray head and its supporting arm;

Fig. 15 is a fragmentary section of a modified arrangement for holding the operating arm against turning on the stem of the valve which controls the outlet passage of the fluid holding container; and

Fig. 16 is an enlarged transverse section taken on line 16a—16a of Fig. 15.

Similar reference numerals throughout the several views indicate the same parts.

In the practice of dentistry it is frequently necessary when filling, pulling or treating the teeth to flush or cleanse the mouth with a suitable fluid or liquid which is preferably supplied in the form of a spray but which may be merely a stream of liquid delivered under suitable pressure. In apparatus of this kind it is desirable to provide for the use of both a cold and a warm stream of fluid or liquid, since both may be required under varying conditions of treatment. Water or other liquid may be used in flushing or cleansing the mouth and the present apparatus is designed in a manner to permit of a quick change from liquid of one temperature to that of another whenever desired.

Referring to the drawings, 10 represents a hollow bracket having a vertically disposed portion 11 arranged for attachment to a suitable support such as the frame or column on

which the usual dental appliances are mounted. The bracket is provided with a horizontally disposed shelf or arm 12 forming a base for the lower end of a casing 13 in which depends 5 a support 14 in the form of a receptacle having an outwardly turned flange 15 engaging the top of the casing and serving as a closure for the latter. The support 14 is preferably made cylindrical in form and depending 10 therein is the fluid holding container embodying the upper and lower sections 16 and 17, the latter being threaded to receive the former. The upper section which forms a closure for the lower section is provided with an annular shoulder which rests on and is supported by the flange 15 of the receptacle 14, Figs. 11 and 12. The receptacle at its lower end is provided with an inwardly extending flange 18 located just beneath the bottom of 20 the fluid holding container. Depending from the flange 18 are studs 19, Fig. 9, which are threaded on their lower ends to receive the correspondingly threaded nuts 20, the shank portions of which project through openings 25 in the shelf 12 of the bracket and the heads of which rest thereon. The nuts serve to clamp the shelf and the casing 13 one upon another, the studs 19 operating to exert a downward pull on the receptacle 14 thereby holding the 30 flange 15 in clamping engagement with the upper end of the casing.

The means for heating the fluid holding container preferably comprises one or more electrical resistance windings or coils 21 located within the space between the casing 13 and receptacle 14 and surrounded by sheets of insulating material 22, Fig. 11.

Projecting upwardly from the base 12 is a pair of lugs 22 carrying a switch plate 23 40 formed of insulating material and upon which is mounted a pair of contacts 24 secured by binding posts 25 the lower ends of which project beneath the switch plate. A lead 26 extends between one of the binding 45 posts and the heating coil and the other lead 27 extends between the coil and a socket member 28 on the bracket, Fig. 9. A short connection 29 extends between the other binding posts on the switch plate and a socket member 30 located opposite the socket member 28. The sockets 28 and 30 are mounted on a support 31 of insulating material which is connected with a rib 32 of the bracket 10 by means of screws 33. The 50 socket members are adapted to receive suitable connections leading from a current supply source (not shown).

Means is provided for automatically opening and closing the circuit when the temperature of the fluid in the container rises above or falls below a predetermined degree, whereby the fluid is retained at the desired temperature under varying conditions of operation. This means is in the form of a 55 thermostat of any suitable type and is de-

signed to be set for breaking the circuit at varying degrees of temperature within the heating chamber in which it is positioned. The thermostat is indicated generally at 34 and is carried on the bottom of the fluid holding container in an enclosing annular wall 35 having lugs 36 thereon for receiving the screws 37 which secure the supporting members 38 for the thermostat. By loosening the screws and swinging said members to one side the thermostat may be readily removed as a unit. The thermostat is connected with the circuit by means of the downwardly extending contact fingers 39 which project within the socket-like portions of the contacts 24 on the plate 23. The contacts 24 are preferably formed by bending spring-like material upon itself to afford the spaced vertically disposed portions 24a which grip the fingers 39 when the latter are forced downwardly between said portions upon proper positioning of the fluid holding container within the receptacle 14. The fingers 39 are detachably held upon lugs 40 on the bottom of the thermostat by screws 41 as shown in Figs. 10 and 11.

Means is provided for insuring proper insertion of the depending fingers 39 between the spaced portions 24a of the contacts 24 when positioning the fluid holding container within the receptacle 14. To this end the flange 18 of the receptacle is provided with a pair of oppositely disposed openings 42 for the downward passage of the lugs 36 on the bottom of the container. When inserting the container within the receptacle the lugs if not in registry with the openings will engage the flange and prevent further downward movement of the container until it is rotated to bring the lugs opposite the openings. During such rotation the contact fingers 39 will be above the upper ends of the contacts 24 and will therefore clear the same. When the lugs are brought into registry with said openings the contact fingers will also be in registry with the openings between the spaced portions 24a of the contacts 24 and upon lowering the container with the parts in this relationship the fingers will move downwardly within the contacts 24 to be gripped by the latter. Removal of the container is readily effected merely by lifting it from the receptacle without rotation so that the lugs 36 will remain in registry with the openings 42 to be drawn therethrough and upon raising the container the contact fingers will disengage the contacts 24.

Means is provided for locking the container within the receptacle 14 in order that it may be rigidly held in proper position therein. This means is mounted in the head or upper section 16 of the container and comprises a plurality of locking pins 43 mounted in horizontally disposed openings within the head radiating from the center thereof. The

outer ends of the pins are sharply pointed at 44 whereby they will more effectively bite into the walls of the receptacle 14 when urged outwardly into engagement therewith. The 5 inner ends of the pins are provided with tapered or beveled portions 45 which are engaged by a correspondingly beveled portion 46 on a vertically disposed screw 47 threaded within the head 16 of the container as shown 10 in Fig. 12. It will be seen that by turning the screw in the proper direction its beveled end 46 will serve to spread or move the locking pins outwardly into locking engagement with the wall of the receptacle thereby 15 securely locking the container within the receptacle.

Extending laterally from the head of the container is an arm 48 carrying a valve casting 49 in which is mounted a vertically disposed regulating valve 50 and a horizontally disposed outlet valve 51. Leading to the regulating valve are vertically and horizontally disposed passages 52 and 53 respectively. The passage 52 is in constant communication with the short tubular member 54 with which is connected a cold water supply conduit 55 arranged for connection with a suitable water supply source under pressure. The cold water pipe is thus in constant communication with the container, the flow being through passages 52 and 53 and the tube 56 within the container which is arranged to discharge at a point adjacent the bottom thereof. The warm water passage 57 leading from the container discharges through the valve 50 when the latter is in the position shown in Fig. 4. The valve 50 is provided with a stem 58 on the upper end of which is an operating handle 59 having 25 a bearing portion 60 rotatable in a nut 61 threaded in the extension 62 of the valve casting 49, Fig. 6. The bearing portion is connected with the stem by a screw 63 threaded into the stem and extending downwardly 30 through a cap 64 on the bearing portion which is clamped in position by the screw. The extension 62 is provided with a semi-circular shelf-like portion 65 on which is a plate 65a having upwardly projecting stop pins 66 located in the path of the valve handle 59 and by which movement of the latter is limited to its extreme positions of adjustment as indicated in Figs. 4 and 5. The 35 plate 65 has applied thereto the words "Cold" and "Tepid" as shown in Fig. 3 for indicating the position to which the handle is moved in order that the valve will be adjusted to permit either the cold or warm water to be used. The outlet passage 67 leading from the regulating valve is normally closed by the valve 51 as indicated in Fig. 4. This valve operates in a chamber 68 communicating with a casing 69 in which is disposed a strainer or filter 70 for the fluid discharging to the nozzle head. Connected

with the container 69 are inner and outer flexible tubes or conduits 71a and 72a respectively which are suitably connected with a combined hand grip and valve casing 73a on the outer end of which is a head 74a carrying the nozzle or spray pipe 75a. A valve within the casing 73a (not shown) is operated by pressing the finger lever 76a inwardly toward the casing at which time the fluid under pressure will flow through the head and the nozzle pipe attached thereto, all of which parts constitute the spray head.

The valve 51 is attached to the operating stem 71 therefor by means of a ball and socket connection indicated generally at 72 30 whereby to better insure the proper seating of the valve under all conditions of operation. The stem is threaded at 73 within a packing nut 74 which is in turn threaded within the casing 49. Suitable packing 75 35 surrounds the valve stem within the nut and the same is compressed by a member 76 threaded within the outer end of the packing nut.

The operating means for the valve stem 71 comprises an arm 77 having a fork 77a at its outer end and provided at its inner end with an enlarged head 78 recessed at 79 to receive the outer end of the packing nut 74 and the member 76 thereon. The valve stem 71 projects through the head 78 and is rigidly connected therewith by a member 80 clamped upon the head by a screw 81 projecting therethrough and threaded into the valve stem as best shown in Fig. 4. The member 80 has a beveled or wedge-shaped portion 82 cooperating with a similarly constructed wedge portion 83 on the outer end of the valve stem whereby to insure rotation of the stem when the operating handle 77 is swung between its extreme positions to open and close the valve 51. The outer end of the head 78 is notched or serrated at 84 and the inner face of the member 80 is likewise serrated at 85 whereby under the clamping action of the screw 81 loosening of said parts is prevented and a better gripping action between the same is afforded.

The packing nut 74 is provided with a cylindrical bearing portion 86 on which is rotatable the sleeve-like portion 78a of the valve stem operating head 78. The bearing portion 86 is reduced at 87 to receive a friction brake comprising a semi-circular spring 88 on which is mounted a brake element 89 urged into engagement with the inner surface of the extension 78a by the spring. The spring and brake element are connected by a stud 90 the head of which is positioned in a recess formed in the reduced portion 87 of the bearing 86. The spring is so tensioned when applied that its ends tend at all times to move outwardly and it thereby serves to yieldably hold the brake element 89 in frictional engagement with the inner wall of

the hollow portion of the head 78. It will be seen therefore that the friction brake serves to hold the operating arm 77 in any position to which it is moved.

5 The spray head may be employed to move the operating arm 77 either to open or close the valve 51. With the arm in the dotted line position shown in Fig. 2 the valve will be open and in the full line position it is 10 closed. By referring to Fig. 14 it will be seen that upon gripping the valve casing 73^a of the spray head and moving it upwardly the shoulder 74^a will engage the bottom portion of the fork 77^a and that continued upward movement of the head will swing the 15 operating arm to the dotted line position indicated. When it is desired to close the valve 51 the spray head is inserted within the fork of the arm and is then drawn downwardly 20 to the full line position shown in Fig. 2, during which time the ball shaped portion of the head will be in engagement with the upper face portion of the fork as shown in Fig. 14. The extent to which the valve 51 25 may be opened will of course depend on the position to which the operating arm 77 is moved by the spray head, it being understood that the arm may be swung to a number of different angular positions to effect rotation 30 of the screw 73 on the stem 71 and the consequent movement of the valve 56.

The flexible conduit connecting the spray head with the fluid holding container is formed of inner and outer tubes 71^a and 72^a, 35 the latter serving to protect the former and thereby increasing the life of the same. The manner of attaching these tubes to the casing 69 is best shown in Fig. 13. In this view a coupling 91 has its lower end projecting 40 into the ends of the flexible tubes upon which said ends are secured in any suitable manner. The coupling is provided with an annular flange 92 engaged by the inturned flange 93 of a nut 94 screwed upon the casing 69 to 45 clamp the flange 92 upon a washer 95 for sealing the joint between the coupling and the casing.

In order to reduce the volume of liquid 50 remaining in the nozzle tube when the valve thereon is closed, I employ a flexible nozzle tube having a capillary opening therethrough for the passage of the fluid. By employing a capillary tube for this purpose the volume of cold water to be discharged upon opening 55 the valve, in advance of the flow of the warm water through the nozzle, is considerably decreased. In other words the capillary tube can be emptied in less time than a larger tube having a greater volume of water to be discharged therefrom and a saving of time is 60 thus afforded which is important in the various dental operations incident to the treatment of the teeth.

In Figs. 15 and 16 I have shown a modified 65 device for preventing relative movement be-

tween the operating arm 77 and the outer portion 83 of the valve stem on which the arm is mounted. In this modification instead of placing the serrations on the outer end of the head 78 they are located within the head 70 as indicated at 85^a in Figs. 15 and 16. The cooperating serrations 84^a are located on the wedge member 82^a which cooperates with the inclined portion of the valve stem 83 to lock 75 the stem and the head of the operating arm 75 together. The remaining parts associated with the head are the same as disclosed in Figs. 4 and 6 and have been given corresponding reference characters.

I claim as my invention:

1. In a device of the class described, a closed container for holding fluid under pressure having separate inlet and outlet passages, a conduit connected with the inlet passage, a flexible tube connected with the outlet passage, a nozzle connected with said tube, a valve for closing the outlet passage having an operating arm connected therewith arranged to receive and support the nozzle and a second valve arranged in one position to close the inlet passage and to establish direct communication between said conduit and the outlet passage and serving in another position to establish communication between the conduit and the inlet passage. 90

2. In a device of the class described, a closed container for holding fluid under pressure having separate inlet and outlet passages and a supply passage leading to the inlet passage, a flexible tube connected with the outlet passage, a nozzle on the flexible tube, a valve on the container for closing the outlet passage, a second valve on the container arranged in one position to close the inlet passage and to establish communication between the supply passage and the outlet passage, an electrical heating device for the container arranged for connection with an electric circuit and means associated with said heating device for automatically breaking the circuit when the fluid in the container is heated to a predetermined temperature. 105

3. In a device of the class described, a closed container for holding fluid under pressure having separate inlet and outlet passages, a conduit connected with the inlet passage, a flexible tube connected with the outlet passage, a nozzle connected with said tube, a valve for closing the outlet passage having an operating arm connected therewith arranged to receive and support the nozzle, a second valve arranged in one position to close the inlet passage and to establish direct communication between said conduit and the outlet passage and serving in another position to establish communication between the conduit and the inlet passage, and electric heating means for the container. 115

4. In a device of the class described, the combination of a container for holding fluid 120

under pressure having inlet and outlet passages, a flexible tube connected with the outlet passage, a nozzle on the tube, a valve for closing the outlet passage, an operating member for the valve arranged to receive and support the nozzle, an electric heating unit for the container arranged to be connected with an electric circuit and a thermostat associated with the heating means for breaking 10 the circuit when the fluid in the container is heated to a predetermined temperature.

5. In a device of the class described, a closed container for holding fluid under pressure having a fluid inlet passage terminating below the top of the container and a fluid outlet passage leading from the container at a point above the discharge end of the inlet passage, a flexible tube connected with the discharge end of the outlet passage, 15 a nozzle on the outer end of the tube, a valve movable to two different positions for connecting either the fluid inlet passage or the fluid outlet passage with the flexible tube, means for indicating when said valve is in 20 said different positions, a second valve for closing the inlet end of the flexible tube whereby to relieve the pressure within the tube and operating means for the second valve forming a support for the nozzle and 25 arranged for movement thereby to open and close the second valve.

OSCAR H. PIEPER.
